UNITED STATES PATENT OFFICE.

JOHN RUTSON VAN TASSEL, OF GENEVA, NEW YORK, ASSIGNOR OF ONE-HALF TO STANDARD OPTICAL COMPANY, OF GENEVA, NEW YORK, A CORPORATION, AND ONE-HALF TO GUSTAV A. BADER, OF ROCHESTER, NEW YORK.

EYEGLASS-MOUNTING.

1,192,712.

Specification of Letters Patent. Patented July 25, 1916.

Application filed August 18, 1915. Serial No. 46,111.

To all whom it may concern:

Be it known that I, JOHN RUTSON VAN TASSEL, a citizen of the United States, and resident of Geneva, in the county of Ontario and State of New York, have invented 5 certain new and useful Improvements in Eyeglass-Mountings, of which the following is a specification.

This invention relates to eyeglass-mountings of the type in which the nose-guards are mounted upon levers which are pivotally connected with a rigid bridge and are controlled by means of springs.

The object of the invention is to produce 15 an eyeglass-mounting, of the type in question, having a simple and convenient construction by which the nose-guard levers are pivoted, and by which these levers and the springs which control them are secured in 20 place, with provision for their easy removal and without the use of the screws usually employed for this purpose.

The invention consists in the eyeglass-mounting hereinafter described, as it is defined in the succeeding claims.

In the accompanying drawings:—Figures 1 and 2 are, respectively, a plan-view and a rear-elevation of a portion of an eyeglass-mounting embodying the present invention, 30 this portion including the parts adjacent one end of the bridge; and Fig. 3 is a rear-elevation of a modified form of the invention.

The eyeglass-mounting illustrated in the drawings comprises the usual lens-clips 1, 35 lens-straps 2, bridge 3 and nose-clamp lever 4. The pivot for the nose-clamp lever is in the form of a pin or stud 5. This stud has a portion, of reduced diameter, which is driven into a vertical perforation at the end 40 of the bridge, and is upset or headed on its lower end to secure it firmly in place. The nose-guard lever 4 is pivoted loosely upon this stud, and rests against the upper flat surface of the bridge.

45 The spring by which the nose-guard lever is controlled comprises a coiled portion 8 which is loosely mounted upon the stud 5. One end 8^b of the spring extends rearwardly and is bent, at its extremity, so as to hook 50 around the outer edge of the nose-guard

lever. The other end 8^a of the spring is formed as a hook, and this hooked extremity engages one end of a pin 6 which is driven into a transverse perforation at the upper end of the stud 5. The pin 6 not only fixes 55 the spring against rotation on the stud, by engagement with the hooked end 8^a, but it also serves to retain the spring upon the stud, and the spring, in turn, presses the nose-guard lever firmly against the upper 60 surface of the bridge. When it is necessary to remove the spring or the nose-guard lever the pin 6 may be readily withdrawn, and the spring and the nose-guard lever may then be raised freely from the stud. This construction 65 is extremely simple and inexpensive, and it avoids the objectionable tendency of the ordinary pivot-screws to work loose. An alternative form of construction is shown in Fig. 3. In this case the pin 6^a, 70 instead of being driven into a perforation in the stud, rests in a slot at the upper end thereof, and the upper end of the stud is also threaded to receive a cap-nut 9 by which the pin and the other parts are secured in 75 place.

I claim:—

1. An eyeglass-mounting having, in combination, a bridge, means for securing the lenses to the bridge, a stud fixed to the 80 bridge at each end thereof and having a transverse opening, a nose-clamp lever loosely pivoted on each stud, a spring having a coiled portion which is loosely mounted on each stud and extends to and engages 85 the corresponding nose-clamp lever, so as to retain the lever against its bearing on the bridge, said coiled portion being of sufficient diameter to pass freely over the end of the stud, and means, for removably securing the 90 spring and the nose-clamp lever in place, comprising a cross-pin seated in said transverse opening in the stud and engaged by the other end of the spring.

2. An eyeglass-mounting having, in combination, a bridge, means for securing the lenses to the bridge, a stud fixed to the 95 bridge at each end thereof and having a slot extending inwardly from its free end, a nose-clamp lever loosely pivoted on each

stud, a spring having a coiled portion which is loosely mounted on each stud and extends to and engages the corresponding nose-clamp lever, so as to retain the lever against its bearing on the bridge, said coiled portion being of sufficient diameter to pass freely over the end of the stud, and means, for

removably securing the spring and the nose-clamp lever in place, comprising a cross-pin seated in said slot and a nut threaded 10 upon the end of the stud and securing said pin in place in said slot.

JOHN RUTSON VAN TASSEL.
